(57) **CLAIM**

The ornamental design for a traffic barrel base as shown and described.

DESCRIPTION

FIG. 1 is a top perspective view of a traffic barrel base according to the present invention;

FIG. 2 is a bottom perspective view of FIG. 1;

FIG. 3 is a top view of FIG. 1;

FIG. 4 is a side view of FIG. 1;

FIG. 5 is a side view of FIG. 1;

FIG. 6 is a side view of FIG. 1;

FIG. 7 is a side view of FIG. 1;

FIG. 8 is a bottom view of FIG. 1; and,

FIG. 9 is an environmental view of FIG. 1 with a traffic barrel shown in broken line.

The broken line showing is included for the purpose of illustrating unclaimed subject matter and forms no part of the claimed design.

1 Claim, 4 Drawing Sheets
